IMPROVED CARPET STRETCHER.

JAMES B. MARTINDALE, OF NEW CASTLE, INDIANA.

Letters Patent No. 60,216, dated December 4, 1866.

SPECIFICATION.

TO ALL WHOM IT MAY CONCERN:

Be it known that I, JAMES B. MARTINDALE, of New Castle, in the county of Henry, and State of Indiana, have invented a new and useful Machine for Stretching Carpets; and I do hereby declare that the following is a full, clear, and exact description of the construction and operation of the same, reference being had to the annexed drawings, making a part of this specification, in which—

My invention relates to constructing or covering a roller, of suitable size, of smooth or roughened India rubber, which is secured in a proper frame; the roller is applied to the surface of the carpet to be stretched, and shoved forward. When sufficiently stretched, the frame is let fall on the floor, and the tacks F F' F'' F''' &c., fig. 1, hold it in place. To give more or less-stretching power, there is a brake, B, hinged on the lower side to cross-piece C, or with pivots working in slots, in ears D D, which is tightened or loosened by means of the screw, H, on the end of the handle, G, pressing against the said brake, B, figs. 1 and 3. The roller is secured in the frame by means of the pivots, J J, and ears, D D, fig. 1. In the under side of the cross-bar, C, are small tacks, F F'', &c., or nails, sharpened, to hold the machine in place while nailing or tacking down the carpet. The frame, including everything except the rubber covering, may be made of metal or wood.

I claim as my invention a carpet stretcher made with a roller covered with India rubber, with or without a roughened surface, the rolling and pressure of which roller are regulated at pleasure by means of the brake B, substantially as set forth.

JAMES B. MARTINDALE.
